SUPERCHARGING CONTROL FOR INTERNAL-COMBUSTION ENGINES

Pierre Lebet, Arbon, Switzerland, assignor to Aktiengesellschaft Adolph Saurer, Arbon, Switzerland

Application March 13, 1943, Serial No. 479,023
In Germany January 9, 1942

7 Claims. (Cl. 123—75)

1

This invention relates to internal combustion engines provided with supercharging means.

It is an object of this invention to improve the supercharging of the cylinders without adding any separate control mechanism.

Since the time interval required for the supercharging coincides with the compression stroke, this interval must be kept as short as possible, since otherwise the supercharging effect would be impaired by the inevitable shortening of the effective compression stroke. Therefore a prerequisite for a satisfactory supercharging effect is the provision of large inlet ports in conjunction with high opening and closing speeds.

It has already been proposed to provide supercharging ports in the cylinder wall which are controlled by a ring valve formed with corresponding slots, in order to obtain higher opening and closing speeds.

According to the present invention in engines of this latter type the cross-sectional area of passage of the supercharging ports is increased considerably and high opening and closing speeds are obtained without additional control members being required, by forming that portion of the cylinder wall which adjoins the row of supercharging ports and has not yet been swept by the working piston when the supercharging period is ended, with an additional row of ports controlled by additional slots in the ring valve, these additional ports and slots being however so dimensioned that during each stroke of the ring valve whereby the first row of supercharging ports is uncovered, the additional ports are first uncovered and then covered again. In other words, the circumferential width of the additional ports and slots is made smaller than the width of the main supercharging ports and their control slots. On the other hand the number of additional ports and slots and also their axial length may be greater than the number and length of the main supercharging ports and their control slots.

In the drawing affixed to this specification and forming part thereof, an embodiment of the invention is illustrated diagrammatically by way of example.

In the drawing

Fig. 1 is a section of the lower part of the 50 combustion cylinder of an engine according to this invention.

Fig. 2 is a section on the line II—II in Fig. 1 and

Figs. 3, 4 and 5 are cylinder developments ii- 55

illustrating the different phases of the supercharging period according to the invention.

Referring to the drawing and first to Figs. 1 and 2, in the cylinder 1 a piston 2 arranged for reciprocation is shown in its outer dead centre position, in which it uncovers the scavenging ports 3 to which scavenging air is supplied through a conduit 4.

Above the scavenging ports 3 a row of main supercharging ports 5 and a second row of additional supercharging ports 6 are provided. Compressed supercharging air is fed to these ports in a manner well known in the art. The ports 5 are arranged in that portion of the cylinder wall which is swept by the piston edge during the supercharging period, while the wall portion, in which the ports 6 are formed, is not yet swept by the piston when the supercharging period has come to an end. The circumferential width of the ports 5 and 6 is somewhat smaller than the width of the intervening wall portion and the width of the additional ports 6 is only about half that of the main ports 5.

On the other hand the number of additional ports 6 is greater than the number of main ports 5. The cylinder 1 is surrounded by a ring valve 8 which is formed with two rows of slots 10 and 11 which correspond in number, size and spacing to the ports 5 and 6, respectively, in the cylinder. The slots 10 and 11 are so staggered relative to each other in the circumferential direction, that in one position of the ring valve all ports 5 and 6 are closed. The valve is oscillated by means of a driving lug 9 acted upon by a rod 14 operating against the action of a spring 15 and being actuated by a cam shaft 16 mounted for rotation in the engine frame and carrying cam means 17 (Fig. 2). The lug 9 is arranged on the ring valve 8 on the level of the interstice between the ports 5 that are controlled by the piston and the ports 6 that are controlled exclusively by the slide valve, whereby the stress exerted by the lug 9 on the sleeve is appropriately distributed.

The stroke of the ring valve is greater than the width of the ports 5 by the amount required for closing said ports in a pressure-tight manner and on the other hand completely uncovering them. The additional ports 6 and the corresponding slots 11 in the valve ring are only about half as wide as the ports 5 and therefore are completely covered when only the first halves of the main ports are uncovered. When the ports 5 are completely uncovered, the additional ports 6 are already closed.

Figs. 3 to 5 illustrate the relative positions of the working piston and the ring valve relative to the supercharging ports at three consecutive times, the ports 5 and 6 in the cylinder wall being schematically illustrated for different time moments. In these figures the slots 3, 5 and 6 in the cylinder wall are shown in full lines, while the slots 10, 11 in the valve ring are shown in dash lines. The contour of the piston and the portion of the cylinder wall swept by the piston 10 are indicated by the chain-dotted line 12 and the hatched surface 13 respectively.

Fig. 3 illustrates the position of the parts at the end of the scavenging period. Here the supercharging ports 5 and 6 are still covered by the ring valve and the piston moving away from the outer dead centre is on the verge of closing the scavenging ports 3. Approximately at the same time the exhaust ports 20 arranged at the upper end of the cylinder are closed by the valves 21.

Fig. 4 illustrates the position of the parts in the middle of the supercharging period. The main ports 5 are half opened, the additional ports 6, being narrower, are open altogether. In the second half of the supercharging period the ring valve uncovers the ports 5 completely, whereas the narrower ports 6 are closed again.

Fig. 5 illustrates the condition existing at the end of the supercharging period. The ports 6 are closed by the ring valve, and the ports 5 are left open by the valve, but are covered by the working piston. As the working piston moves on, the compression stroke begins. After the additional ports 6 have been covered also by the working piston, the ring valve 8 is returned into its initial position shown in Fig. 3.

The mechanism above described as forming an object of the invention acts toward improving the supercharging of the cylinders by increasing during the first part, for instance during the first half, of a normal supercharging period the cross-sectional area of the passage admitting the supercharging medium into the cylinders.

I wish it to be understood that I do not desire to be limited to the exact details shown and described, for obvious modifications will occur to a person skilled in the art.

I claim:

1. An internal combustion engine comprising in combination, a cylinder and a piston arranged for reciprocation therein, exhaust ports in said cylinder near the compression stroke end of said piston, exhaust valve for said ports, a ring valve concentric with and contacting said cylinder, and two pairs of registering belts of intake ports arranged in axial alignment in said valve and in the part of the cylinder wall swept by said piston respectively, said pairs of parts being controlled by said ring valve, the ports in the belts nearer to the compression stroke end of said cylinder being materially narrower than the ports in the belts farther away from said cylinder end, and means for oscillating said ring valve.

2. An internal combustion engine comprising in combination, a combustion cylinder and a piston arranged for reciprocation therein, exhaust ports in said cylinder near the compression stroke end of said piston, exhaust valve for said ports, a ring valve concentric with and contacting said cylinder, and two pairs of registering belts of intake ports arranged in axial alignment in said valve and in the part of the cylinder wall swept by said piston, respectively, said pairs of ports being controlled by said ring valve, the ports in the belts nearer to the compression stroke end of said cylinder in the direction of the movement of the ring valve, being about one half of the width of the ports in the belts farther remote from said cylinder end.

7. An internal combustion engine comprising in combination, a cylinder and a piston arranged for reciprocation therein, exhaust ports in said

the belts nearer to the compression stroke end of said cylinder being materially narrower and of greater axial length than the ports in the belts farther from said cylinder end, and means for oscillating said ring valve.

3. An internal combustion engine comprising in combination, a combustion cylinder and a piston arranged for reciprocation therein, exhaust ports in said cylinder near the compression stroke end of said piston, exhaust valves for said ports, a ring valve concentric with and contacting said cylinder and two pairs of registering belts of intake ports arranged in axial alignment in said valve and in the part of the cylinder wall swept by said piston respectively, said pairs of ports being controlled by said ring valve, the ports in the belts nearer to the compression stroke end of said cylinder being materially narrower and of greater axial length and more narrowly spaced than the ports in the belts farther from said cylinder end, and means for oscillating said ring valve.

4. An internal combustion engine comprising in combination, a combustion cylinder and a piston arranged for reciprocation therein, exhaust ports in said cylinder near the compression stroke end of said piston, exhaust valve for said ports, a ring valve concentric with and contacting said cylinder and two pairs of registering belts of intake ports arranged in axial alignment in said valve and in the part of the cylinder wall swept by said piston respectively, said pairs of ports being controlled by said ring valve, the ports in the belts nearer to the compression stroke end of said cylinder being about half as wide and about double as long as the ports in the belts farther from said cylinder end, and means for oscillating said ring valve.

5. An internal combustion engine comprising in combination, a combustion cylinder and a piston arranged for reciprocation therein, exhaust ports in said cylinder near the compression stroke end of said piston, a belt of intake ports in the cylinder wall near the suction-stroke end of the cylinder and two additional belts of intake ports in the cylinder wall in axial alignment with said first belt, a ring valve concentric with and contacting the part of said cylinder formed with said two additional belts of intake ports, said valve being formed with two belts of ports registering with said additional cylinder ports, the intake ports in said cylinder and said valve which are next to the compression stroke end of said cylinder being narrower than the intake ports forming the axially adjoining belts and means for oscillating said ring valve.

6. An internal combustion engine comprising in combination, a cylinder and a piston arranged for reciprocation therein, exhaust ports in said cylinder near the compression stroke end of said piston, an oscillatory ring valve concentric with and contacting said cylinder and two pairs of registering belts of intake ports arranged in axial alignment in said valve and in the part of the cylinder wall swept by said piston, respectively, the width of the ports in the belts nearer to the compression stroke end of said cylinder in the direction of the movement of the ring valve, being about one half of the width of the ports in the belts farther remote from said cylinder end.

cylinder near the compression stroke end of said piston, an oscillatory ring valve concentric with and contacting said cylinder and two pairs of registering belts of intake ports arranged in axial alignment in said valve and in the part of the cylinder wall swept by said piston, respectively, the width of the ports in the belts nearer

to the compression stroke end of said cylinder in the direction of the movement of the ring valve, being about one half of the width of the ports in the belts farther remote from said cylinder end, the stroke of the ring valve being about equal to the width of the latter ports.

PIERRE LEBET.
